Primary Examiner—Doris V. Coles
Attorney, Agent, or Firm—Banner & Witcoff, Ltd.**[57] CLAIM**

The ornamental design for a portion of a shoe outsole, as shown and described.

DESCRIPTION

FIG. 1 is a perspective view of a portion of a shoe outsole showing my new design;

FIG. 2 is a bottom plan view thereof;

FIG. 3 is a profile view of the portion of a shoe outsole of FIG. 1 taken along the line 3—3 of FIG. 2;

FIG. 4 is a profile view of the portion of a shoe outsole of FIG. 1 taken along the line 4—4 of FIG. 2;

FIG. 5 is a profile view of the portion of a shoe outsole of FIG. 1 taken along the line 5—5 of FIG. 2;

FIG. 6 is a profile view of the portion of a shoe outsole of FIG. 1 taken along the line 6—6 of FIG. 2; and,

FIG. 7 is a profile view of the portion of a shoe outsole of FIG. 1 taken along the line 7—7 of FIG. 2.

The broken line showing of a shoe upper and the remaining portion of the sole in FIGS. 1-7 is for illustrative purposes only and forms no part of the claimed design.
